PORTABLE LOCKED COPY TICKET WRITER

John C. Condon, Oak Park, Ill., assignor of one-half to Whitney K. Munson, Red Bank, N.J.

Application October 21, 1948, Serial No. 55,737

14 Claims. (CL 282—5)

1

This invention relates to devices of the type and kind used in making out sales slips of various kinds, wherein a portable device is employed and a definite record maintained of all sales, within the device. More particularly, the invention deals with a portable device of the character described wherein the recorded or locked copy sheet is drawn from a folded pile and wound upon a receiving reel. Further, wherein the initial sales slip is automatically discharged from the device and arranged by hand, upon a writing surface of the device, said surface including a sheet of transfer material for transferring the recordings of the sale sheets to the copy sheet. Still more particularly, the invention deals with a device of the character described wherein a simple means is provided for discharging the sale slips one at a time during the operation of positioning a new copy sheet in the writing or recording area of the device.

The novel features of the invention will be best understood from the following description when taken together with the accompanying drawings, in which certain embodiments of the invention are disclosed, and in which the separate parts are designated by suitable reference characters in each of the views; and in which:

Fig. 1 is a longitudinal section through a device or apparatus made according to my invention and illustrating the operation of feeding a copy sheet from a folded lay in the device to a receiving spool.

Fig. 2 is a plan view of the device as seen in Fig. 1, omitting the cover, except for the sectional illustration thereof at the ends of the device, and showing parts of the construction broken away.

Fig. 3 is a perspective view of the device diagrammatically illustrating a sales ticket preparatory for attachment or mounting on the top of the device.

Fig. 4 is an enlarged sectional view on the line 4—4 of Fig. 2.

Fig. 5 is a partial section on the line 5—5 of Fig. 3, illustrating the automatic delivery of a sales ticket from the casing of the device.

Fig. 6 is a perspective view of the spool on which the locked copy is wound, showing the parts of the spool in detached relationship to each other, to indicate the method of removing the copy sheets in rolled form from the device; and

Fig. 7 is a partial diagrammatic section on the line 7—7 of Fig. 3, to indicate the method

of mounting the carbon or transfer sheet in the device.

In illustrating one adaptation and use of my invention, I have shown in the accompanying drawing, a locked copy ticket writer which can be briefly referred to as a writer device, comprising a main casing 10, composed of two primary parts, namely a body part 11 and a cover part 12. The body part 11 comprises a long bottom wall 13 having upstanding side walls 14 and 15. Considering Fig. 3 of the drawing, it will appear that the walls 14 and 15 have at the end portions thereof, a bevelled part, as best seen at 16 in Fig. 4 of the drawing. The cover 12 is shaped, as seen at 17, to conform with this bevel, thus reducing the vertical dimensions of what may be termed, the upper end 18 of the device. The walls 14 and 15 at the other, or lower end 19 of the device, are rounded to form the rounded edge portion 20 on the cover. This construction results in what may be termed a streamlining of the entire device.

The bottom wall 13 at the reduced end 18 of the device is fashioned to form two pairs of bearings 21, at side portions thereof, to receive a hinge or pivot pin 22, which pin protrudes beyond the sides of the device, including the cover 12, and has attached thereto, a U-shaped handle member 23. This handle member can be extended, as seen in Fig. 3 of the drawing, for convenient carrying of the device, or can be collapsed in the position shown in Fig. 1, when the device is used upon a desk or table.

Secured to the bottom wall 13, at both ends thereof and adjacent the corners of said wall, are rubber or similar cushioned supporting feet 24, the depth of which are greater than that of the handle 23, so as to maintain the handle within the boundaries of the feet, as clearly seen in Fig. 1.

The cover 12 has inturned side edges, one of which is seen at 25, in Fig. 3 and is also indicated in Fig. 4, and these edges extend to receive the pivot or pintle pin 22, the end wall of the cover also being fashioned to form bearings, as at 26, which substantially encircle the pin 22, as clearly seen in Fig. 4. One of these walls is recessed or set inwardly at its end, as seen at 27 in Fig. 4, to receive a reduced end portion 28 on a flap or cover member 29, the reduced end portion 28 having an angularly extending flange portion 30 which extends into the casing and has a bevelled edge as at 31, this structure being clearly seen in Fig. 4 of the drawing. The flap or cover member 29 is generally of the shape

indicated in Fig. 3, and includes curved bearing portions adjacent the ends thereof, one of which is seen at 32, in Fig. 4, these bearing portions engaging the pin 22 in pivotal support of the cover member.

A suitable coil spring 33 is mounted on the pin 22 adjacent one end of the cover 29 and engages the cover to normally support the same in closed position. The primary cover 12 is recessed, as seen at 34, for reception of the flap closure or supplemental cover 29 and is arranged to lie flushly therein, as will clearly appear from a consideration of Fig. 1. However, the flap 29 is extended in the manner later described, to open position in the operation of automatically projecting a sales slip from the device.

Arranged within the body part of the casing is a tray-like receptacle 35 upon which is supported a folded stack or pile of copy sheets 36 which are adapted to be withdrawn from the container tray 35 and wound upon a receiving spool 37, in the manner later described. Supported at the contracted end of the tray 35 is a transversely disposed channel-shaped member 38, over which and partially within which is arranged a cylinder 39, preferably with a frictional facing 40. The cylinder 39 is mounted in suitable bearings in the side walls 14 and 15 in the body portion of the device and the spindle of the cylinder, has at one end, a gear or pinion 41, note Fig. 2. This gear or pinion 41 meshes with another idler pinion 42, having a suitable mounting on the wall 14 and the idler pinion in turn meshes with a large gear 43, mounted on a transverse shaft 44. The major portion of the shaft 44 is split to receive a flexible and friction type feed vein or flap 45 which controls automatic projection of sales tickets 46 one at a time through the opening 34 of the cover, as later described. The shaft 44 has suitable bearings in the side walls 14 and 15, as will be apparent.

Slidably mounted on the wall 14 adjacent the end 18 of the device is a cam plate 47 for actuating the flap or supplemental cover 29. The plate 47 has a cam surface 48 operatively engaging the surface 31 in accomplishing this result, as will be clearly seen in Fig. 4. A rivet pin 49 operates in an elongated aperture 50 in the plate 47 in guiding the movement thereof and also in limiting movement in both directions. The plate 47 has an upwardly offset shoulder portion 51 which is adapted to be engaged by a roller or pin 52 secured to the outer surface of the gear 43 adjacent the periphery thereof, so that in each revolution of the gear, the plate 47 will be advanced to move the flap 29 into open position. The spring on the flap 29 returns the same automatically to closed position and this spring also moves the plate 47 inwardly.

A flap operating rod or bar 53 is slidably mounted on the inner surface of the wall 14 and has a large finger-piece rivet or button 54 disposed outwardly of the wall 14 and operating in an elongated aperture 55 in said wall, note Fig. 3. The bar 53 has at one end portion, an inwardly offset finger 56 which overlies the plate 47 and aids in guiding said plate in its movement and this offset finger forms a shoulder 57 adapted to strike the end 59 of the plate in manually advancing the plate to open the flap 29. The bar 53 has at its other end, an angularly offset flange 59, note Fig. 2, operating upon the wall of the tray or receptacle 35 in guiding the bar in its movement in the device.

Secured to the inner surface of the gear 43 is

a stop pin 60 which, when the mechanism is at rest, seats upon the upper edge of a spring arm 61, secured to the wall 14, as at 62. On the arm 61 is secured a button 63. The arm 61 is tensioned to normally maintain the same in position to be engaged by the pin 60. However, by pressing inwardly upon the button 63, the pin 60 is released to facilitate rotation of the gear 43.

The sales tickets 46 are arranged in a compartment 64 disposed below the tray or receptacle 35, the bottom wall of the receptacle 35 being cut out to form two downwardly extending stops, one of which is shown at 65 in Fig. 1, which limits inward movement of the tickets 46. At the end portion 18 of the device, the bottom wall of the receptacle 35 has forwardly directed angular extensions 66 which guide side edges of the tickets 46 into and out of the compartment 64. In one side of the compartment and engaging one side edge of the tickets, is a suitable friction pad 67 and engaging the opposite side edge of the tickets is a long spring arm 68, note Fig. 2. The arm 68 urges the tickets in engagement with the friction member 67 so that all of the tickets are held against displacement, and an uppermost ticket only can be forcibly withdrawn or projected by the member 45.

The cover 12 has a large rectangular opening 69, as may be clearly seen in Fig. 3 of the drawing, one end of the opening being defined by an upwardly turned or extending retainer flange 70 and on the cover adjacent the other end of the opening are two sales ticket aligning pins 71. Mounted in connection with the cover to close the opening 69 is an inked ribbon sheet 72, similar in structure to conventional typewriter ribbon, in other words having properties to transfer script markings from one sheet to an underlying sheet. The sheet 72 is held in position by a bordering frame 73, clearly illustrated in Fig. 7 of the drawing. Adjacent the flange 70, a hinge or pivot pin 74 is supported in the walls 14 and 15 and pivotally mounted on the pin is a backing sheet 75, which forms a writing surface or sheet supporting surface. The plate 75 has at its free end lateral extensions 76 which engage notched portions 77 on the side walls of the receptacle 35, in alining the plate in the device and also in providing a support for the plate.

Mounted on the pivot rod 74, centrally thereof, is a loop-shaped spring 78 which is adapted to bear against the copy sheet 36, where it is wound upon the spool 37 to maintain this sheet under tension at all times.

The upper wall of the cover 12, adjacent and between the pin 71 has a window opening 79 through which a sales ticket number on the copy sheet 36 will appear. It will be understood that this number will correspond to the number on the sales ticket 46 disposed upon the top of the device. The ticket 46 preferably includes a thin tissue-like, or transparent backing 46', which is indicated only in Fig. 3, in order to simplify the showing. The backing sheet 46' is employed in forming a second copy sheet. This sheet or the ticket 46 can be given to the customer and the other retained for the files. Each ticket 46, including its backing, has a pair of apertures 80 spaced to fit upon the alining pins 71, whereas the other ends of the ticket sheets are adapted to be placed beneath the flange 70, when said sheets are mounted in position for use.

Slidably mounted in the end portion 18 of the device and on the bottom wall 11, is a yoke-shaped lock plate 81, having side arms 82, held in posi-

tion upon the bottom wall by inturned keepers 83, stamped from the walls 14 and 15. The free end of the cover 12 has at its sides, inwardly extending flanges 84, over which the arms 82 are arranged to hold and positively retain the cover against swinging opening movement. A cross-head 85 of the yoke-shaped lock plate 81 has centrally thereof, an aperture 86, note Fig. 1, adapted to be engaged by a key actuated lock element 87 which is operated through a suitable key lock mechanism 88 supported upon the bottom wall 11 of the device. In Fig. 1, the parts are shown in locked position. However, when the lock mechanism 88 is operated, the element 87 will draw the arms 82 inwardly sufficiently to release the flanges 84, permitting the cover 12 to be swung into open position on its pivot 32.

The spool 37 comprises two substantially similar spool halves 89-89', each having a disc end 90-90', the latter having circumferentially spaced apertures 91. Secured centrally of each disc is a rod or spindle part 92-92' having a bevelled surface 93-93' and a notched or recessed central portion 94-94', the latter forming a copy sheet end receiving aperture, as indicated at 37' in Fig. 1 of the drawing. Each spool disc 90-90' has in alignment with the surface of the rod 92-92', an arc-shaped aperture 95-95' adapted to receive the tapered end 96-96' of the opposed part. In other words, in assembling the spool halves, the two halves are forced together with their bevelled surfaces abutting with the ends 96-96' wedged into the apertures 95' and 95, respectively. This maintains the spool assemblage. However, after a complete copy sheet length has been wound upon the spool, the spool is removed, and the halves 89-89' pulled apart, thus leaving a cylindrical roll of the copy sheets, which can be filed away for recording, or other purposes.

The spool 37 is mounted in the device by engaging one end of the spool with a crank or drive shaft 97 supported in connection with the wall 15, the shaft having an end 98 engaging a central aperture in one of the discs 90-90', one of these apertures being shown at 99 on the disc 90 in Fig. 6. A corresponding aperture in the other disc of the spool is engaged by a pin end 100 of a spring-arm 101, note Fig. 2. The spring arm 101 forces the spool into and retains the same in engagement with the end 98 of the shaft 97. The shaft 97 outwardly of the wall 15 has a suitable operating means, such for example, as a crank 102 and on the inner end of the shaft is an arm 103, having a pin end 104 engaging one of the apertures 91-91' of one of said discs. It will be understood that the spool is universal with respect to its mounting in the device so that either disc end can be engaged by the pin end of the arm 103, which acts as a supplemental crank arm.

In the use of the device, the cover 12 is swung into open position and the supporting table 75 swung into raised position and a folded sheet stack of the copy sheets 36 arranged in the receptacle 35, in the manner illustrated in Fig. 1. One end of the sheet is then threaded downwardly around the cylinder 39 and the table member 75 is swung into its operative position, the sheet is then brought upwardly over the table member and the end of the sheet 37 is preferably provided, by pre-arrangement, with a reduced tongue or flap end, as for example, commonly used with photographic film. This end is then passed through the aperture 37' of the spool 37 and the

spool is turned, by hand, until the first sheet 36 is brought into a predetermined position on the table 75. Suitable means may be provided on the sheet 36 to gage this positioning. When so positioned, the stop pin 60 is in the locked position, as seen in Fig. 4 of the drawing. The device is also loaded with a predetermined number of sales tickets 46 which are disposed in the compartment 64. This can be done when the cover 12 is in the open position or can also be accomplished after the cover has been closed and the supplemental cover or closure flap, which may also be termed a door, is manually moved by the bar 53 into open position.

When the device is loaded in the manner described, the cover 12 is moved into closed position and locked through the lock mechanism 88. The device is now ready for use.

In use, the button 63 is first pushed inwardly to release the lock pin 60. While held in this position with one hand, the crank 102 is operated with the other hand, and after crank action has been started, the button 63 can be released and the crank is rotated until such time that the pin 60 again engages the spring arm 61 and the mechanism is at rest. This operation has now drawn the first copy sheet 36 in position beneath the carbon or transfer sheet 72 and a number on the sheet 36 will appear in the opening 79.

During the aforesaid operation, the gear 43 will have completed one revolution, returning the stop pin 60 to the position shown in Fig. 4. During this revolution, the flexible friction ticket delivery member 45 will have been flexed between the supporting rod or shaft 44 and the surface of the yoke or channel member 38 and then released to establish frictional engagement with the uppermost sales ticket 46, in the manner diagrammatically shown in Fig. 5. Simultaneously upon the engagement of the member 45 with the sales ticket and in starting outward feed or delivery of the uppermost ticket, the pin 52 engages the shoulder 51 on the plate 47 and automatically moves the flap or door 29 into open position. The uppermost ticket is sufficiently projected by the member 45 to be freely grasped by the hand and the operator withdraws this ticket, after which the flap or door 29 automatically moves into closed position. This last operation again returns the plate to its normal position.

The removed ticket 46 will have the same number thereon as the copy sheet ticket disposed beneath the opening 69. The sales ticket is then mounted beneath the flange 70 and upon the pins 71 and the device is now ready for recording of the first sale. In making the next sale, the above cycle of operation is repeated, and a second copy ticket is brought in position beneath the opening 69, another sales ticket removed and placed in position upon the device and in this second operation, the first copy ticket is automatically wound upon the spool 37. This operation continues until such time as the sales tickets 46 are consumed, whereupon the operator automatically and manually opens the flap or door 29 and places the next series of sales tickets in the compartment 64 and this operation continues until the copy sheet tickets have been consumed or substantially so. It will be understood from the foregoing, that the sales tickets 46 are of a heavier structure than the copy sheet tickets 36, and therefore, a greater number of the copy sheets 36 can be included in the device, but the procedure outlined is not objectionable and in fact desirable from the stand-

point of maintaining a relatively light device and one with a minimum thickness. After the first folded stock of copy tickets 36 has been consumed and wound on the spool 37, the device is turned in to the office or clerk for keeping the recordings and the device is unlocked, the spool removed, as heretofore stated, and a new stack will be placed in the device for further use by the sales clerk.

In sales ticket devices, machines or apparatus of the kind defined, it has been customary to employ relatively large machines having means for feeding a number of sheets upon a writing surface, the sheets generating from rolls or piles. In some instances, means have been provided for storage of copy sheets or tickets in what might be termed a locked copy writer or machine. In most instances, these machines have been so heavy and bulky as to require counter use thereof. Furthermore, the machines have been complicated and thus expensive in initial purchase and further in maintenance thereof.

With my improved simple and portable device, the desired application of noting sales on sales slips and keeping a definite locked copy record thereof is simplified and accomplished in a manner where the device can be utilized on a counter or conveniently carried about and supported in the hand, in the operation of recording sales. One of the distinctive features in this device resides in the use of sales tickets or sheets which are automatically projected from the device in the operation of positioning a copy sales sheet in the device with which the projected sheet has a definite association and relationship and in the manual placement of the sales ticket or sheet on the machine and removal of the same therefrom when the sale has been completed. Furthermore, the utilization of the split spool upon which the locked copy is wound is a distinctive feature of the invention from the standpoint that it provides a simple and practical means for removal of the copy sheet, in a roll, from the machine by an authorized individual for safekeeping and for checking with sales made. This method of procedure insures a more perfect control and recording of all sales, particularly in that the locked copy is not available to the sales person and cannot be tampered with in any way. Still further, the provision of the manual means for opening the compartment in which sales tickets are arranged enables the sales person to replenish the sales ticket supply from time to time during a period of a continued recording of sales on the locked copy sales slip.

In considering the operation of my improved device, it will be understood that the drive from the winding spool to the gear mechanism of the device is through the medium of the copy sheet which has its frictional engagement with the drive cylinder. Thus, feed is governed by the length of the copy sheet so that numerals of successive sheets will be brought into registering alinement with the opening in the cover and independent of winding of the sheet upon the spool. In other words, having definitely controlled positioning of the copy sheet. No possible difficulty can be experienced with respect to registrations of the sales ticket sheets therewith in that the latter is at all times manually placed in a definite predetermined position on the device and with respect to said copy sheet.

It will be apparent that the sheet or fabric forming the transfer sheet 12 may be adhesively or otherwise attached to the frame 13, and thus

75 form a unit attachable and detachable with respect to the cover. This particular attachment can be accomplished in any desired manner.

While I have referred to the use of sales tickets 5 of heavy stock, it will be understood that this is desirable only in some uses of the device, where the ticket is subject to rough handling.

Having fully described my invention, what I claim as new and desire to secure by Letters Patent is:

1. A device of the class described comprising an elongated casing formed from a body part of U-shaped cross-sectional form and a cover part forming a closure for the first named part, means 15 hingedly mounting one end of the cover part to the corresponding end of the body part, the cover part having a large opening forming a writing field therein, a transfer element disposed in said field, a table member in said body part beneath and spaced from said field and element, means 20 within the body part for storing an elongated strip of paper characterized to form a successive series of copy sheets, said strip being adapted to pass between said element and table member, 25 means comprising a spool in one end portion of the body part for winding said sheet to feed successive copy sheets in predetermined registered position beneath said writing field and element and upon said table member, the body part having means 30 for storing a plurality of independent sales tickets therein, said casing having an opening, through which a ticket is adapted to pass, and means actuated by said strip winding means in feed of one of said copy sheets to said predetermined position for projecting one of said sales tickets from the device to be accessible for manual withdrawal therefrom.

2. A device of the class described comprising an elongated casing formed from a body part of 40 U-shaped cross-sectional form and a cover part forming a closure for the first named part, means hingedly mounting one end of the cover part to the corresponding end of the body part, the cover part having a large opening forming a writing field therein, a transfer element disposed in said field, a table member in said body part beneath and spaced from said field and element, means 45 within the body part for storing an elongated strip of paper characterized to form a successive series of copy sheets, said strip being adapted to pass between said element and table member, means comprising a spool in one end portion of the body part for winding said sheet to feed successive copy sheets in predetermined registered position beneath said writing field and element and upon 50 said table member, the body part having means for storing a plurality of independent sales tickets therein, said casing having an opening, through which a ticket is adapted to pass, means actuated by said strip winding means in feed of one of said copy sheets to said predetermined position for projecting one of said sales tickets from the device to be accessible for manual withdrawal therefrom, and means bordering said writing field for 55 alining and supporting the withdrawn ticket over said field in registering position with said sheet.

3. A device of the class described comprising an elongated casing formed from a body part of U-shaped cross-sectional form and a cover part forming a closure for the first named part, means hingedly mounting one end of the cover part to the corresponding end of the body part, the cover part having a large opening forming a writing field therein, a transfer element disposed in said field, a table member in said body

part beneath and spaced from said field and element, means within the body part for storing an elongated strip of paper characterized to form a successive series of copy sheets, said strip being adapted to pass between said element and table member, means comprising a spool in one end portion of the body part for winding said sheet to feed successive copy sheets in predetermined registered position beneath said writing field and element and upon said table member, the body part having means for storing a plurality of independent sales tickets therein, said casing having an opening, through which a ticket is adapted to pass, means actuated by said strip winding means in feed of one of said copy sheets to said predetermined position for projecting one of said sales tickets from the device to be accessible for manual withdrawal therefrom, means bordering said writing field for alining and supporting the withdrawn ticket over said field in registering position with said sheet, a cylinder frictionally engaged by said strip, and means actuated by said cylinder controlling and checking extent of feed of the strip in the device.

4. A device of the class described comprising an elongated casing formed from a body part of U-shaped cross-sectional form and a cover part forming a closure for the first named part, means hingedly mounting one end of the cover part to the corresponding end of the body part, the cover part having a large opening forming a writing field therein, a transfer element disposed in said field, a table member in said body part beneath and spaced from said field and element, means within the body part for storing an elongated strip of paper characterized to form a successive series of copy sheets, said strip being adapted to pass between said element and table member, means comprising a spool in one end portion of the body part for winding said sheet to feed successive copy sheets in predetermined registered position beneath said writing field and element and upon said table member, the body part having means for storing a plurality of independent sales tickets therein, said casing having an opening, through which a ticket is adapted to pass, means actuated by said strip winding means in feed of one of said copy sheets to said predetermined position for projecting one of said sales tickets from the device to be accessible for manual withdrawal therefrom, means bordering said writing field for alining and supporting the withdrawn ticket over said field in registering position with said sheet, a cylinder frictionally engaged by said strip, means actuated by said cylinder controlling the checking extent of feed of the strip in the device, a spring actuated door controlling an opening through which a sales ticket is projected, and manually actuated means for moving said door into open position.

5. A device of the class described comprising an elongated casing formed from a body part of U-shaped cross-section form and a cover part forming a closure for the first named part, means hingedly mounting one end of the cover part to the corresponding end of the body part, the cover part having a large opening forming a writing field therein, a transfer element disposed in said field, a table member in said body part beneath and spaced from said field and element, means within the body part for storing an elongated strip of paper characterized to form a successive series of copy sheets, said strip being adapted to pass between said element and table member, means comprising a spool in one end

portion of the body part for winding said sheet to feed successive copy sheets in predetermined registered position beneath said writing field and element and upon said table member, the body part having means for storing a plurality of independent sales tickets therein, said casing having an opening, through which a ticket is adapted to pass, means actuated by said strip winding means in feed of one of said copy sheets to said predetermined position for projecting one of said sales tickets from the device to be accessible for manual withdrawal therefrom, means bordering said writing field for alining and supporting the withdrawn ticket over said field in registering position with said sheet, a cylinder frictionally engaged by said strip, means actuated by said cylinder controlling the checking extent of feed of the strip in the device, a spring actuated door controlling an opening through which a sales ticket is projected, manually actuated means for moving said door into open position, and said table member being pivotally supported in the body part.

6. A device of the class described comprising an elongated casing formed from a body part of U-shaped cross-sectional form and a cover part forming a closure for the first named part, means hingedly mounting one end of the cover part to the corresponding end of the body part, the cover part having a large opening forming a writing field therein, a transfer element disposed in said field, a table member in said body part beneath and spaced from said field and element, means within the body part for storing an elongated strip of paper characterized to form a successive series of copy sheets, said strip being adapted to pass between said element and table member, means comprising a spool in one end portion of the body part for winding said sheet to feed successive copy sheets in predetermined registered position beneath said writing field and element and upon said table member, the body part having means for storing a plurality of independent sales tickets therein, said casing having an opening, through which a ticket is adapted to pass, means actuated by said strip winding means in feed of one of said copy sheets to said predetermined position for projecting one of said sales tickets from the device to be accessible for manual withdrawal therefrom, means bordering said writing field for alining and supporting the withdrawn ticket over said field in registering position with said sheet, a cylinder frictionally engaged by said strip, means actuated by said cylinder controlling the checking extent of feed of the strip in the device, a spring actuated door controlling an opening through which a sales ticket is projected, manually actuated means for moving said door into open position, said table member being pivotally supported in the body part, and tensional means engaging the copy sheet wound on said spool to maintain the sheet in taut position in the device at all times.

7. A device of the class described comprising an elongated casing formed from a body part of U-shaped cross-sectional form and a cover part forming a closure for the first named part, means hingedly mounting one end of the cover part to the corresponding end of the body part, the cover part having a large opening forming a writing field therein, a transfer element disposed in said field, a table member in said body part beneath and spaced from said field and element, means within the body part for storing an elongated strip of paper characterized to form a successive

series of copy sheets, said strip being adapted to pass between said element and table member, means comprising a spool in one end portion of the body part for winding said sheet to feed successive copy sheets in predetermined registered position beneath said writing field and element and upon said table member, the body part having means for storing a plurality of independent sales tickets therein, said casing having an opening, through which a ticket is adapted to pass, means actuated by said strip winding means in feed of one of said copy sheets to said predetermined position for projecting one of said sales tickets from the device to be accessible for manual withdrawal therefrom, means bordering said writing field for alining and supporting the withdrawn ticket over said field in registering position with said sheet, a cylinder frictionally engaged by said strip, means actuated by said cylinder controlling the checking extent of feed of the strip in the device, a spring actuated door controlling an opening through which a sales ticket is projected, manually actuated means for moving said door into open position, said table member being pivotally supported in the body part, tensional means engaging the copy sheet wound on said spool to maintain the sheet in taut position in the device at all times, and means comprising a locked mechanism in the body part operatively engaging the cover part to seal said spool against unauthorized displacement from the device.

8. A device of the class described comprising an elongated casing formed from a body part of U-shaped cross-sectional form and a cover part forming a closure for the first named part, means hingedly mounting one end of the cover part to the corresponding end of the body part, the cover part having a large opening forming a writing field therein, a transfer element disposed in said field, a table member in said body part beneath and spaced from said field and element, means within the body part for storing an elongated strip of paper characterized to form a successive series of copy sheets, said strip being adapted to pass between said element and table member, means comprising a spool in one end portion of the body part for winding said sheet to feed successive copy sheets in predetermined registered position beneath said writing field and element and upon said table member, the body part having means for storing a plurality of independent sales tickets therein, said casing having an opening, through which a ticket is adapted to pass, means actuated by said strip winding means in feed of one of said copy sheets to said predetermined position for projecting one of said sales tickets from the device to be accessible for manual withdrawal therefrom, and said means comprising an elongated strip of flexible friction material rotatably mounted in the body part and operatively engaging the upper surface of the uppermost sales ticket stored therein.

9. In a device of the class described, employing an elongated relatively narrow casing with a writing field on one surface thereof, a transfer element in said field, a table beneath the element, a spool sealed in said device, in which an elongated copy ticket strip stored in said casing is adapted to be wound, manually actuated means for intermittently actuating the spool to deliver a copy ticket in the field between said element and table, means within the device for storing and frictionally supporting a plurality of individual sales tickets with one end of the sales tickets adjacent one open end of the casing, 75

means in said end of the casing and arranged above the uppermost sales ticket in said storage and actuated by said first named means for projecting an uppermost ticket through the opening in said end of the casing for accessibility to an operator for manual withdrawal from the device, and means on the device for positioning and holding the withdrawn sales ticket in alinement with said re-positioned copy ticket.

10. In a device of the class described, employing an elongated relatively narrow casing with a writing field on one surface thereof, a transfer element in said field, a table beneath the element, a spool sealed in said device, in which an elongated copy ticket strip stored in said casing is adapted to be wound, manually actuated means for intermittently actuating the spool to deliver a copy ticket in the field between said element and table, means within the device for storing and frictionally supporting a plurality of individual sales tickets with one end of the sales tickets adjacent one open end of the casing, means in said end of the casing and arranged above the uppermost sales ticket in said storage and actuated by said first named means for projecting an uppermost ticket through the opening in said end of the casing for accessibility to an operator for manual withdrawal from the device, means on the device for positioning and holding the withdrawn sales ticket in alinement with said re-positioned copy ticket, and said ticket projecting means comprising a transversely arranged elongated flexible body of friction material rotatably mounted in the device.

11. In a device of the class described, employing an elongated relatively narrow casing with a writing field on one surface thereof, a transfer element in said field, a table beneath the element, a spool sealed in said device, in which an elongated copy ticket strip stored in said casing is adapted to be wound, manually actuated means for intermittently actuating the spool to deliver a copy ticket in the field between said element and table, means within the device for storing and frictionally supporting a plurality of individual sales tickets with one end of the sales tickets adjacent one open end of the casing, means in said end of the casing and arranged above the uppermost sales ticket in said storage and actuated by said first named means for projecting an uppermost ticket through the opening in said end of the casing for accessibility to an operator for manual withdrawal from the device, means on the device for positioning and holding the withdrawn sales ticket in alinement with said re-positioned copy ticket, said ticket projecting means comprising a transversely arranged elongated flexible body of friction material rotatably mounted in the device, a door closing said opening in the casing, and tensional means for supporting the door in closed position.

12. In a device of the class described, employing an elongated relatively narrow casing with a writing field on one surface thereof, a transfer element in said field, a table beneath the element, a spool sealed in said device, in which an elongated copy ticket strip stored in said casing is adapted to be wound, manually actuated means for intermittently actuating the spool to deliver a copy ticket in the field between said element and table, means within the device for storing and frictionally supporting a plurality of individual sales tickets with one end of the sales tickets adjacent one open end of the casing, means in said end of the casing and arranged

above the uppermost sales ticket in said storage and actuated by said first named means for projecting an uppermost ticket through the opening in said end of the casing for accessibility to an operator for manual withdrawal from the device, means on the device for positioning and holding the withdrawn sales ticket in alinement with said re-positioned copy ticket, said ticket projecting means comprising a transversely arranged elongated flexible body of friction material rotatably mounted in the device, a door closing said opening in the casing, tensional means for supporting the door in closed position, and automatically actuated means for moving the door into opened position in projection of the sales ticket through said opening.

13. In a device of the class described, employing an elongated relatively narrow casing with a writing field on one surface thereof, a transfer element in said field, a table beneath the element, a spool sealed in said device, in which an elongated copy ticket strip stored in said casing is adapted to be wound, manually actuated means for intermittently actuating the spool to deliver a copy ticket in the field between said element and table, means within the device for storing and frictionally supporting a plurality of individual sales tickets with one end of the sales tickets adjacent one open end of the casing, means in said end of the casing and arranged above the uppermost sales ticket in said storage and actuated by said first named means for projecting an uppermost ticket through the opening in said end of the casing for accessibility to an operator for manual withdrawal from the device, means on the device for positioning and holding the withdrawn sales ticket in alinement with said re-positioned copy ticket, and means detachably supporting the spool in the device.

14. In a device of the class described, employing an elongated relatively narrow casing with a writing field on one surface thereof, a transfer element in said field, a table beneath the element, a spool sealed in said device, in which an elongated copy ticket strip stored in said casing is adapted to be wound, manually actuated means for intermittently actuating the spool to deliver

a copy ticket in the field between said element and table, means within the device for storing and frictionally supporting a plurality of individual sales tickets with one end of the sales tickets adjacent one open end of the casing, 5 means in said end of the casing and arranged above the uppermost sales ticket in said storage and actuated by said first named means for projecting an uppermost ticket through the opening in said end of the casing for accessibility to an operator for manual withdrawal from the device, means on the device for positioning and holding the withdrawn sales ticket in alinement with said re-positioned copy ticket, means detachably supporting the spool in the device, and said spool 10 comprising separate similar parts facilitating quick detachment of the rolled copy sheet therefrom.

JOHN C. CONDON.
